SPECIFICATION forming part of Design No. 19,929, dated June 24, 1890.

Application filed June 2, 1890. Serial No. 364,056. Term of patent 7 years.

To all whom it may concern:

Be it known that we, WILLIAM J. KEEP and CHARLES WIPFLER, citizens of the United States, residing at Detroit, in the county of Wayne and State of Michigan, have invented 5 certain new and useful Improvements in a Design for a Stove, of which the following is a specification, reference being had therein to the accompanying drawing.

10 This design is intended for heating-stoves, and the essential features thereof are shown in the accompanying photograph.

Referring now to said photograph by letter, A represents a dome having a series of crossed ribs a, making diamond and triangular shaped recesses a', below which are a plain ring B and an ornamental border, consisting, mainly, of imitation basket-work b', with two scrolls b'' in the center, below which is a plain project-

20 ing ring C. The body D of the stove is of cylindrical form and is provided with two doors E E'. The upper door has openings surrounded by intertwined scroll-work, forming ovals, which

scrolls are continued outside of and partly 25 under the ovals to form an oblong border. The lower door E' is ornamented with a raised shield e and leaves e' at the corners. On each side of the doors is a strip of ornamentation F, simulating basket-work. Below 30 the doors and these ornamental strips is a plain ring G, from which depend hangers H, ornamented by scroll-work and carrying a second plain ring I. Immediately under the ring G is a fluted fire-pot J, resting on a base 35 K, having openings k in front, between which are scrolls k'. This base is provided with legs L, ornamented with leaves and scrolls.
